ADOLPH A. GAZDA, OF WILKINSBURG, PENNSYLVANIA, ASSIGNOR TO WESTINGHOUSE ELECTRIC & MANUFACTURING COMPANY, A CORPORATION OF PENNSYLVANIA.

SWITCH MECHANISM.

1,354,181.

Specification of Letters Patent. Patented Sept. 28, 1920.

Application filed November 19, 1917. Serial No. 202,701.

To all whom it may concern:

Be it known that I, ADOLPH A. GAZDA, a citizen of the United States, and a resident of Wilkinsburg, in the county of Allegheny and State of Pennsylvania, have invented a new and useful Improvement in Switch Mechanisms, of which the following is a specification.

My invention relates to switch mechanisms and particularly to switch mechanisms for governing the operation of electric motors.

One object of my invention is to provide a switch mechanism of the above-indicated character that shall be simple, rugged, and relatively inexpensive in construction and reliable and effective in operation.

In accelerating an electric motor, and particularly in accelerating a shunt-wound direct-current motor, it is essential to provide a resistor in the armature circuit which shall be short-circuited, either manually or automatically, when the motor is operating at normal speed. In many cases, a number of resistors, which are successively short-circuited in accordance with the current flowing through the motor, are initially inserted in series with the motor armature. When a motor-control system is provided with a number of resistors, as in the example last mentioned, and it is desired to automatically short circuit the same it is customary to provide a set of switches, separate from the resistor-short-circuiting switches, that are operated in a predetermined order in accordance with the current flowing through the motor for effecting the operation of the resistor-short-circuiting switches. The auxiliary accelerating switches are somewhat expensive in construction and add somewhat more of apparatus to the control system.

In a motor-control system provided with switch mechanisms that are constructed in accordance with my invention, the resistor-short-circuiting switches are provided with auxiliary switches which are controlled by the resistor switches in a manner to automatically effect operation of the resistor switches in accordance with the current flowing through the motor. Each of the resistor switches is provided with an auxiliary switch which is held in an open position by means of a spring mechanism. An armature is associated with the energizing coil of the resistor switch in a manner to release

the spring mechanism when the resistor switch is operated. However, when the resistor switch is operated and the spring mechanism is released, the blowout coil which is associated with the resistor switch is energized and serves to hold the auxiliary switch in an open position until the current flowing through the motor has been reduced sufficiently to permit the closing of the next resistor-short-circuiting switch.

In the accompanying drawing, Figure 1 is a side elevational view of a switch mechanism constructed in accordance with my invention. Fig. 2 is a front elevational view of the switch mechanism illustrated in Fig. 1, and Fig. 3 is a plan view of the switch mechanism illustrated in Figs. 1 and 2. Fig. 4 is a diagrammatic view of a plurality of interconnected switch mechanisms.

Referring to the accompanying drawing, a switch mechanism 1, embodying a main switch 2 and an auxiliary switch 3, is mounted upon an insulating support 4. The main switch 2 embodies a pair of relatively movable contact terminals 5 and 6, an energizing coil 7, and a blowout coil 8. The contact member 5 is pivotally mounted on an armature 9 which is adapted to be attracted by the energizing coil 7. The armature 9, which is pivotally mounted on a magnetizable frame 10, is provided with a projection 11 for engaging a lug 12 to prepare an auxiliary magnetic circuit for a purpose to be set forth hereinafter.

The auxiliary switch 3 embodies an arm 13, which is pivotally supported upon a bracket 14, an armature 15, which is joined to the arm 13 and is associated with the blowout coil 8, and a contact member 16 which is adapted to bridge contact terminals 17 and 18 when the auxiliary switch 3 is operated. The contact terminals 17 and 18 are connected in circuit with the coil 7 of the next succeeding switch 2, as is diagrammatically represented at Fig. 4.

A spring mechanism 19, which acts in opposition to a spring 20, is provided for maintaining the auxiliary switch 3 in an open position when the main switch 2 is deenergized. The spring mechanism 19 embodies a rod 21 which passes through the support 4 and the arm 13 of the switch 3 and is provided with enlarged heads 22 and 23 near the ends thereof. The head 23 of the rod 21 is adapted to engage the arm 13,

and a coil spring 24 is disposed around the rod 21, intermediate the head 22 and the insulating support 4, in a manner to maintain the auxiliary switch 3 in an open position.

An armature 25, which is pivotally mounted upon the insulating support 4, is disposed in a position to be attracted by the main energizing coil 7 when the same is energized for operating the main switch 2. When the armature 9 is attracted by the coil 7, a magnetic circuit is prepared for the armature 25 that includes the armature projection 11, the lug 12, and a lug 26 which projects from the coil of the electromagnet. The armature 25 is so disposed in relation to the spring device 19 that one end thereof is adapted to engage the head 22 of the rod 21 in order to compress the spring 24 and release the auxiliary switch 3 whenever the armature 25 is attracted by the energizing coil 7.

When it is desired to operate the switch mechanism 1, a circuit is completed through the energizing coil 7 for attracting the armature 9. As soon as the magnetic circuit for the energizing coil 7 is completed by the armature 9, sufficient flux is produced for attracting the armature 25 in order to compress the spring 24 and permit the releasing of the spring mechanism 19. However, when the main switch 2 is closed and the spring mechanism 19 is released by the armature 25, the blowout coil 8 is energized so as to attract the armature 15 of the auxiliary switch 3 and prevent the closing of the auxiliary switch at this time. The action of the blowout coil 8 of the armature 15 is opposed by the spring 20 and, when the motor current flowing through the blowout coil 8 is sufficiently reduced, the auxiliary switch 3 is closed by the spring 20 for energizing the next resistor-short-circuiting switch.

In the system illustrated in Fig. 4, an electric motor 30 has an armature 31 and a series field-magnet winding 32. The motor circuit and a starting resistor 33 are controlled by a series of switches of the type illustrated in Figs. 1, 2 and 3, similar numerals being employed to designate corresponding parts. It will be readily understood that the auxiliary switch 3 is omitted from the last switch to close. A push-button switch 34, controls a circuit comprising the actuating coils 7 of the main switches and the auxiliary switches.

Upon the actuation of the push-button switch 34, the first switch of the series operates in the manner described above in connection with Figs. 1, 2 and 3 to effect the closing of the motor circuit and subsequently to effect the closing of the auxiliary switch 3 when the current traversing the motor circuit has fallen to a predetermined value. The coil 7 of the succeeding switch

to close is energized and the operation described above is repeated until the entire resistor is shunted.

The various switches and circuits of the system are restored to their initial positions upon the opening of the push-button switch 34.

Modifications in the apparatus and arrangement and location of parts may be made within the spirit and scope of my invention and such modifications are intended to be covered by the appended claims.

I claim as my invention:

1. In a switch mechanism, the combination with a main switch having an energizing and a blowout coil, and an auxiliary switch biased to its open position, of means controlled by said energizing coil for effecting the closing of said auxiliary switch, and means controlled by the blowout coil for permitting the closing of the auxiliary switch under predetermined conditions.

2. In a switch mechanism, the combination with a main switch having an energizing coil, a blowout coil in circuit with the main switch, and an auxiliary switch controlled by said energizing coil, of a spring for holding the auxiliary switch in an open position, and means whereby the operation of the auxiliary switch is controlled by said blowout coil.

3. In a switch mechanism, the combination with a main switch having an energizing and a blowout coil, and an auxiliary switch having a spring mechanism for maintaining the same in an open position, of means controlled by said energizing coil for releasing the spring mechanism, and means controlled by the blowout coil for permitting the closure of the auxiliary switch under predetermined conditions.

4. In a switch mechanism, the combination with a main switch and an auxiliary switch associated with the main switch, of means controlled in accordance with the position of said main switch for maintaining the auxiliary switch in its open position, and a blowout coil associated with the main switch for permitting the operation of the auxiliary switch under predetermined conditions.

5. In a switch mechanism, the combination with a main switch having a blowout coil associated therewith, of an auxiliary switch normally maintained in its open position, common means for effecting the closure of said main switch and said auxiliary switch, and means controlled by said blowout coil for preventing the closing of said auxiliary switch under predetermined conditions.

6. In a switch mechanism, the combination with a main switch having a blowout coil associated therewith, and an auxiliary switch, of means for biasing said auxiliary

switch to its open position, and means jointly controlled by the main switch and the blowout coil for permitting the operation of the auxiliary switch under predetermined conditions.

7. In a switch mechanism, the combination with a main switch having an energizing coil, of an auxiliary switch, a spring mechanism for maintaining the auxiliary switch in its open position, means for releasing the spring mechanism when the main coil is energized, and a blowout coil associated with the main switch for releasing the auxiliary switch under predetermined conditions.

8. In a switch mechanism, the combination with a main switch having an energizing and a blowout coil, an auxiliary switch, and a spring mechanism for maintaining the auxiliary switch in an open position, of an armature controlled by said energizing coil for releasing the spring mechanism when the main switch is operated, and means controlled by the blowout coil for holding the auxiliary switch in its open position for a predetermined length of time after the same is released by the spring mechanism.

9. In a switch mechanism, the combination with a main switch having an energiz-

ing and a blowout coil, an auxiliary switch, and a spring mechanism for holding the auxiliary switch in its open position, of an armature controlled by said energizing coil for releasing the spring mechanism when the main switch is operated, and means comprising an armature associated with the auxiliary switch and controlled by the blowout coil for holding the auxiliary switch in its open position for a predetermined period of time after the main switch has been operated.

10. In a switch mechanism, the combination with a main coil, a main switch operated by said coil, a blowout coil associated with said main switch, and an auxiliary switch controlled by said blowout coil and maintained in its open position thereby under predetermined conditions, of a spring mechanism for maintaining said auxiliary switch in its open position when the main coil is deenergized, and an armature associated with the main coil for releasing the spring mechanism when the main coil is energized.

In testimony whereof I have hereunto subscribed my name this 30th day of Oct., 1917.

ADOLPH A. GAZDA.
